UNITED STATES PATENT OFFICE.

HARLIN BROWN, OF MAYFIELD, MICHIGAN.

WOODEN COLUMN.

No. 846,450.

Specification of Letters Patent.

Patented March 12, 1907.

Application filed September 21, 1906. Serial No. 335,595.

To all whom it may concern:

Be it known that I, HARLIN BROWN, a citizen of the United States, residing at Mayfield, in the county of Grand Traverse and State of Michigan, have invented new and useful Improvements in Wooden Columns, of which the following is a specification.

This invention relates to the art of making wooden columns, and particularly solid wooden columns as distinguished from those built up of longitudinal staves or pieces.

Previous to this invention in the manufacture of columns or posts they have either been made solid of one piece of wood, which was exceedingly expensive, or were made of a number of veneered pieces glued together, which after a few years pull apart on account of the failure of the glue, or were made of several thin pieces dovetailed or otherwise put together and glued and which are apt to spread apart in a comparatively short time.

The object of my invention is to eliminate these objectionable features and to otherwise improve and cheapen the manufacture of solid columns of the kind stated.

By means of this invention a column may be made of two or more pieces of wood, particularly those pieces called "bolts" which are a by-product of veneering-mills. The wood does not have to be of the same kind; but the column may be composed of several pieces of any kind of wood, such pieces being held together securely and rigidly by dowels of wood or steel or by any other suitable means, the whole being then covered by a suitable veneer—such, for example, as Manila paper, cloth, or other suitable material—which will cover all defects, knots, worm-holes, and other imperfections or blemishes.

The invention is furthermore capable of application to and includes the making of capitals and bases for columns, pilasters, and the like. Hitherto capitals have been made of solid turned pieces or else built up of several pieces and then turned to the desired shape. Making capitals and bases of one piece of material is not only expensive, but causes delay, as material of large diameter is difficult to obtain, and if the capitals and bases are constructed of two or more pieces glued together eventually they will become separated to more or less extent. Furthermore, capitals, bases, and fillets are apt to become chipped and damaged in transporta-

tion. I overcome these objections by constructing the bases, capitals, and the like of one or more pieces of molding which are bent around the columns, half-columns, or other shapes and securely fastened to the same with brads or the like, and can thus be put in place when the columns, &c., are set up.

The invention is illustrated in the accompanying drawings, in which—

Figure 1 is an elevation of a column constructed according to the invention. Fig. 2 is a section on the line A B of Fig. 1. Fig. 3 is a side elevation of a half-column. Fig. 4 is an end view of the column. Fig. 5 is a horizontal cross-section on the line C D of Fig. 1. Fig. 6 is a horizontal section on the line E F of Fig. 3.

Referring specifically to the drawings, *a*, *b*, and *c* indicate three wooden bolts or cores of wood superposed or standing one upon the other and held together by wooden dowels *d* and steel dowels *s*, preferably arranged in a ring around the wooden dowels. The bolts or pieces are turned to the proper diameter to match at their abutting ends. The body so constructed is covered with any suitable veneer, as indicated at *p*. This may preferably be Manila paper, cloth, or other suitable material glued upon the body, so as to cover the joints between the bolts or sections and give the appearance of a one-piece column, which can then be painted or otherwise decorated.

The base, capital, and a fillet on the column are indicated as built up of one or more pieces of molding *m*, which are bent around the column and tacked or otherwise secured thereto.

A column or shape so constructed has the advantage heretofore indicated, as well as a special advantage of cheapness, since bolts or pieces may be used of much less length than the total height of the column, which would consequently be otherwise incapable of use for the purpose.

I claim—

1. As a new article of manufacture, a wooden column comprising a plurality of solid superposed blocks permanently secured together at the abutting ends, and having a continuous exterior coating, forming a unitary structure having the appearance and attributes of a one-piece column and capable of transportation and manipulation as such.

2. As a new article of manufacture, a wooden column comprising a plurality of solid blocks secured together end to end and covered with veneer extending across the joints between the blocks to conceal the same and assist in holding the blocks together, and giving the article the appearance and qualities of a one-piece column.

3. As a new article of manufacture, a sectional column consisting of wood veneered

with a web of fabric permanently secured thereon and forming the outer exposed coating thereof.

In testimony whereof I have signed my name to this specification in the presence of 15 two subscribing witnesses.

HARLIN BROWN.
